UNITED STATES PATENT OFFICE.

THOMAS H. LOVEJOY, OF CHICAGO, ILLINOIS.

PUNCH.

SPECIFICATION forming part of Letters Patent No. 770,238, dated September 13, 1904.

Application filed September 23, 1903. Serial No. 174,261. (No model.)

To all whom it may concern:

Be it known that I, THOMAS H. LOVEJOY, a citizen of the United States, residing in Chicago, in the county of Cook and State of Illinois, have invented a new and useful Improvement in Punches, of which the following is a specification.

My invention relates to improvements in punches for punching holes in metal.

10 Metal-punches have heretofore generally been made in the form of a solid tool or punch which is secured to the stock by a threaded coupling or nut, a separate tool or punch being required for each different size of hole desired to be formed. This requires a very large number of punches or tools and also considerable expense, and if one of the punches or tools of a larger size happens to break, although the fracture may occur at its point 15 or smaller end, the whole tool is ruined and requires to be thrown away. Also in the larger size of solid punches difficulty is frequently experienced in properly hardening and tempering the tool without causing internal strain, weakness, and liability to fracture.

The object of my invention is to provide a compound metal-punch so that the same punch may be used for punching holes of a plurality 30 of different sizes and so that in case of breakage, which usually occurs at the smaller or pointed end of the punch, only a comparatively small and inexpensive piece of the hardened tempered tool-steel will be lost, thus 35 effecting a very great saving of expense.

My invention consists in the means I employ to accomplish this result—that is to say, it consists, in connection with the punch-stock and threaded coupling or nut, of a hollow 40 punch or punch-shell and a smaller solid punch fitting or nesting in the hollow punch or shell and a thrust-block fitting in the hollow punch or shell and interposed between the smaller solid punch and the thrust-block, so that the 45 smaller solid punch will serve, in combination with the hollow punch or shell, as the lower or pointed end thereof in making larger holes of the size of the shell and also serve as the small punch in making holes of the size of 50 the solid punch.

My invention further consists in a plurality of hollow punches or shells fitting or nesting one within another in connection with a smaller solid punch fitting in the smaller punch or shell.

As the punch-shell or punch-shells which are used in my invention in forming the larger-sized holes are hollow, it will be readily understood that they can be readily hardened and tempered without danger of injury, and 55 as in my invention any breakage of the punch-point only effects the small solid punch, which is a comparatively small piece of tool-steel, it can be renewed at little expense, and the punch-shells, which are the larger and more 60 expensive pieces, are seldom liable to fracture.

In the accompanying drawings, forming a part of this specification, Figure 1 is a side elevation, partly in vertical section, of a punch embodying my invention. Fig. 2 is a central 70 vertical section through the compound punch. Fig. 3 is a section on line 3 3 of Fig. 2. Fig. 4 is a detail perspective view of the small solid punch, and Fig. 5 shows a modification in which only one hollow punch or punch-shell is employed.

In said drawings, A represents the die; X, the plate of steel or other metal to be punched; A², the stripper-plate; B, the threaded coupling or nut, and C the stock to which the 80 punch is secured by the coupling or nut and by which it is reciprocated or operated.

D is a hollow punch or punch-shell used for making larger-sized holes. D' is a second hollow punch or punch-shell fitting and nesting in the punch-shell D, and D² is a smaller solid punch fitting and nesting in the smaller punch D'. 85

F and F' are thrust-blocks interposed between the smaller solid punch D² and the 90 thread-stock C, the thrust-block F fitting in the larger hollow punch or shell D and abutting at its lower end against the hollow punch D' and the thrust-block F', which abuts against the head d of the lower or solid punch D². 95 The head d of the solid punch D² has a conical or exterior bevel-shoulder d' fitting the corresponding interior bevel-shoulder d² in the hollow punch or shell D', and the head or upper end d³ of the hollow punch D' has a cor- 100

responding exterior bevel-shoulder d' fitting the corresponding interior bevel-shoulder d^2 on the hollow punch D. The head or upper end d^4 of the hollow punch D has an exterior bevel-shoulder d' , which fits the interior bevel-shoulder b of the coupling or nut B. The length of the thrust-blocks F and F' are such as to tighten the several nesting punches in each other and take up all slack or lost motion.

I do not herein claim the subject-matter shown in Fig. 5, as that forms the subject of my divisional application.

I claim—

15 1. The combination with a punch-stock and threaded coupling or nut, of a plurality of hollow punches fitting and nesting one within another, a solid punch fitting and nesting in the smaller hollow punch, and thrust-blocks fitting in the hollow punches and interposed between the smaller solid punch and the stock, substantially as specified.

20 2. The compound punch herein shown and described and comprising in combination a punch-stock, coupling, and a plurality of hollow punches fitting and nesting together and each having an internal and an external shoul-

der, and a solid punch fitting in the smaller hollow punch and having an external shoulder or head engaging the internal shoulder of the 30 smaller punch, and thrust-blocks fitting in the hollow punches and interposed between the solid punch and the punch-stock, substantially as specified.

3. The combination with a punch-stock C, 35 threaded coupling B secured thereto and having an internal bevel-shoulder b of punch-shell D having an external bevel-shoulder d' engaging said internal bevel-shoulder b of the coupling, and provided with an internal bevel-shoulder d^2 , smaller punch-shell D' fitting and nesting within said punch-shell D and having an external bevel-shoulder and an internal bevel-shoulder, and solid punch D² fitting and nesting within said punch-shell D' and having 45 an external bevel-shoulder, and thrust-blocks F and F' fitting within said punch-shells and interposed between said solid punch and said punch-stock, substantially as specified.

THOMAS H. LOVEJOY.
